UNITED STATES PATENT OFFICE.

BENJAMIN THOMAS DAGGY, OF RICHMOND, INDIANA.

SURGICAL APPARATUS.

Application filed July 13, 1927. Serial No. 205,462.

This invention relates to surgical apparatus and has for the primary object the provision of means designed to be worn by females to act as a uterine drain or conductor of fluids from the uterus to a container or receptacle, without permitting the fluids to come in contact with the middle or lower vaginal vault and canal, or tissues, or other internal and external parts.

- 10 Another object of the invention is the provision of an apparatus of the above character which may be worn with comfort and convenience at menstrual periods, as well as for the purpose of draining the uterine cavity in cases of hemorrhage due to cancer, fibroids and other affections of that organ and thereby help prevent infection of the parts external thereto and permit them to be kept in a clean and sanitary condition.
- 15 Another object of the invention is the provision of an apparatus which will support the vaginal vaults and assist in maintaining the normal position of the uterus at times when it is congested and heavy, and thus greatly relieve otherwise painful periods of menstruation.

Another object of the invention is the provision of an apparatus which will support a prolapsed uterus and a prolapsed urinary bladder, while the upper vaginal vault is being drained.

Another object of the invention is the provision of an apparatus which may be easily and quickly taken apart for cleaning, and thereafter readily reassembled, so that it may be kept in a sanitary condition.

Another object of the invention is the provision of an apparatus which in addition to the above and other advantageous features, is made of soft flexible rubber and other suitable materials, with the parts so constructed and arranged that it may be adjusted to any size vaginal vault and worn without discomfort or annoyance and without danger of injury to the wearer.

With the above and other objects in view, the invention further includes the following novel features and details of construction, to be hereinafter more fully described, illustrated in the accompanying drawings and pointed out in the appended claims.

In the drawings:—

- Figure 1 is a sectional view illustrating the invention.
- 55 Figure 2 is a section on the line 2—2 of Figure 1.

Figure 3 is a fragmentary elevation partly in section illustrating the manner of removably connecting the shield and transforming cup or chamber to the neck of the apparatus. 60

Figure 4 is a horizontal section taken through the neck of the apparatus just above the point of attachment of the shields.

Figure 5 is an enlarged section on the line 5—5 of Figure 1. 65

Referring to the drawings in detail wherein like characters of reference denote corresponding parts, the reference character 10 indicates the head portion of the apparatus which is connected to the body 11 by a neck 16. 70

The head portion which is designed to be inserted within the upper or inside vaginal cavity is substantially cylindrical in shape and includes an outer wall 13 which is preferably formed of expandible rubber, and an inner wall 14 which extends through the head and defines a passage through said head. The wall 14 is preferably formed of soft nonexpandible rubber and is so shaped that the passage defined thereby tapers from the top to the bottom of the head. The wall 14 is extended so as to provide a neck 15 of the same material. Extending along the neck 15 is a tube 16 whose inner end opens into the head, or into an air chamber 17 whose walls are formed by the walls 14 and 13. The outer or opposite end of this tube 16 is provided with a removable closure cap 18 and the tube provides means whereby the head 10 may be conveniently inflated so as to entirely fill the 85 walls of the vaginal cavity.

Permanently secured to the lower end of the neck 15 is a ring 19 which is formed of suitable material and which is externally threaded. Threadedly and detachably engaging the ring 19 is a ring 20 which has extending therefrom studs or buttons 21. Secured over these studs or buttons 21 are the inner ends of oppositely extending preferably rubber shields 22 whose outer ends carry 100 rings 23 and provide means whereby the apparatus may be secured to the wearer's garment, or to a cord or belt, a portion of which is indicated by the dotted lines at 24 in Figure 1 of the drawings. 105

Also attached to the ring 20 over the studs 21 is a container 25 which is divided by a partition 26 into an upper chamber 27 and a lower chamber 28. This container is provided with a flexible neck portion 29 having openings 110 therein for receiving the studs 21. The partition 26 is provided with openings 30 so as to

provide communication between the chambers 27 and 28.

Located within the upper chamber 27 is a cup-shaped transforming compartment or chamber 31 which is also provided with a flexible neck portion indicated at 32. This neck portion 32 has openings for the passage of the studs 21, so that the container 25 and the cup-shaped transforming chamber 31, as well as the shields 22, may be separated or removed from the ring 20 and the latter removed from the ring 19. The parts may thus be readily separated for the purpose of cleaning and thereafter readily and conveniently reassembled.

The cup-shaped transforming chamber carries at its upper end a thin flexible diaphragm 32'. This diaphragm is preferably formed of rubber and is arranged beneath the lower end of the neck 15 so as to permit of the passage of fluids through the neck into the transforming chamber 31, but will prevent return passage of said fluids. The diaphragm 32' thus in effect forms a check valve. This diaphragm carries a screen covered compound of non-coagulants, deodorants, bleaching chemicals and antiseptics which are pressed or formed into thin blocks and indicated at 33. The block 33 is thus arranged in the path of fluids passing from the neck 15. The action of the compounds forming the block is to prevent the blood from coagulating and provide a deodorant and antiseptic.

The transforming chamber is provided with openings 34 through which the fluid passes from this chamber into the chamber 27 of the receptacle 25. Before passing from the transforming chamber 31 however the fluid is further subjected to the action of another screen covered compound formed of the same materials as the block 33. This last referred to screen covered compound is substantially cup-shaped and is indicated at 35. This compound covers the bottom and extends upward along the sides of the chamber 31 and acts upon the fluid within this chamber to further prevent the blood from coagulating to provide a deodorant and antiseptic. Additional pawls or blocks 36 of the same compound are arranged within the chamber 31 to sterilize the fluids and prevent odors.

Extending around the upper portion of the chamber 31 is a shield 37. This shield extends over the openings 34 and acts to prevent the walls of the container 25 from closing the openings 34 should the container walls become partially deflated.

After the fluid has been acted upon by the elements 33, 35 and 36, it passes out through the openings 34 into the upper chamber 27 and through the openings 30 into the lower chamber 28. A tube 38 has one of its ends suitably secured to the container 25 so as to drain this container. The opposite end of

this tube is in communication with a container 39 which is preferably provided with a cover 40. This cover carries straps 41. The container 39 is designed to be attached to the thigh of the wearer and is shaped in conformity therewith so that it may be conveniently secured in place, or may be secured within a special pocket provided in one of the garments of the wearer so as not to be noticeable. If desired, the container 39 may be omitted.

The container 25 is arranged within a flexible sack-like casing 42 whose upper ends are secured as at 43 to the shields 22. In addition, the outer end of the tube 16 is suitably secured to one of the shields 22 as indicated at 44.

The invention is susceptible of various changes in its form, proportions and minor details of construction and the right is herein reserved to make such changes as properly fall within the scope of the appended claims.

Having described the invention what is claimed is:

1. A surgical apparatus comprising an expandible head portion open at its end and adapted to be expanded to fill the inner vaginal cavity, a non-expandible passage extending through the head portion, a body, a hollow neck connecting the head portion and body, a container within the body, a transforming cup interposed between and communicating with the neck and container, transforming chemicals within the transforming cup and means to secure the apparatus in position for use.

2. A surgical apparatus comprising an expandible head portion open at its end and adapted to be expanded to fill the inner vaginal cavity, a non-expandible passage extending through the head portion, a body, a hollow neck connecting the head portion and body, a container within the body, a transforming cup interposed between and communicating with the neck and container, transforming chemicals within the transforming cup and a detachable container upon the outside of the body and communicating with the container within the body.

3. A surgical apparatus comprising an expandible head portion open at its end and adapted to be expanded to fill the inner vaginal cavity, a non-expandible passage through the head portion, a body, a hollow neck connecting the head portion and body, a container within the body, a transforming cup interposed between and communicating with the neck and container, a pressure operated check valve controlling communication between the neck and transforming cup, transforming chemicals within the transforming cup and means to secure the apparatus in position for use.

4. A surgical apparatus comprising an expandible head portion open at its end and

adapted to be expanded to fill the inner vaginal cavity, a non-expansible passage extending through the head portion, a container extending from the lower end of the neck portion, a transforming cup having openings therein to provide communication with the container, a guard extending around the transforming cup and spaced outwardly from the openings, a transforming chemical within the cup and means to secure the apparatus in position for use.

5. A surgical apparatus comprising a head portion adapted to be positioned within the inner vaginal cavity and having a passage therethrough, a hollow neck extending from one end of the passage, a container extending from the neck, a transforming cup within the container and having communication with the neck and container, means to detachably secure the transforming cup and container to the neck and means to secure the apparatus in position for use.

6. A surgical apparatus comprising a head portion adapted to be positioned within the inner vaginal cavity and having a passage

therethrough, a hollow neck extending from one end of the passage, a container extending from the neck, a transforming cup within the container and having communication with the neck and container, means to detachably secure the transforming cup and container to the neck, a guard removably secured to the neck, a sack carried by the guard around the container and means to secure the apparatus in position for use.

7. A surgical apparatus comprising a head portion adapted to be positioned within the inner vaginal cavity and having a passage therethrough, a hollow neck extending from one end of the passage, a container extending from the neck, a transforming cup within the container and having communication with the neck and container, a guard extending from the neck, a ring removably secured to the neck, means to detachably secure the guard, transforming cup and container to the ring and means extending from the guard to secure the apparatus in place.

In testimony whereof I affix my signature.
BENJAMIN THOMAS DAGGY.
